UNITED STATES PATENT OFFICE

2,589,426

INJECTOR

Robert W. Ogle, Pasadena, Calif.

Application November 25, 1949, Serial No. 129,438

14 Claims. (Cl. 128—215)

1

This invention relates to injectors and more particularly to an injector for injecting various sera, inoculations, and the like, between and beneath the layers of the skin. It is a primary object of this invention to provide such an injector, which is very easy to use and which is provided with safeguards which insure its proper functioning, no matter how little experienced the operator.

It is a further object of this invention to provide such an injector which is very inexpensive and which can thus be designed for one use and then be thrown away.

It is a further object of this invention to provide such an injector which can be loaded with the serum, inoculation, or the like, at a central laboratory and sold in a filled condition for subsequent dispensing.

It is a further object of this invention to provide safety means in the giving of injections which prevent too deep an injection of the serum or inoculation.

It is a feature of this invention that the needle is so disposed with respect to the planning guide that the tip of the needle will be in practice disposed at exactly the desired depth beneath the surface of the skin. It is generally desirable in making intradermal injections to provide that the injection will be made below the epidermis and just above the corium. Accordingly, it is a feature of this invention that the tip of the needle is adjusted to make just this depth of penetration in the skin in normal persons. However, it is sometimes desired to make just a narrow furrow in the skin, and accordingly the invention contemplates that the needle may be disposed at a shallower depth or, as otherwise expressed, at a more acute angle to the horizontal. Again in other types of injections, a greater depth of injection is desired, and this invention contemplates that the needle may be adjusted for such deeper or subcutaneous injection.

These and other objects, features and advantages of the invention will be apparent from the annexed specification in which:

Figure 1 is an isometric perspective elevation of the device embodying the present invention;

Figure 2 is a plan view; and

Figure 3 is a fragmentary vertical section.

Referring now more particularly to the drawings, this invention comprises a base or plane member 10 having formed integrally therewith a post 11 in the form of a hollow cylinder. A finger grip 12 in the form of an upstanding fin is also formed integrally with the base member 10. To-

wards the forward part of the device the base 10 is cut out as at 13 and 14. The base 10, post 11 and fin 12 are preferably formed of poly-ethylene plastic and the walls of the post 11 are considerably thinner than the walls of the base 10 or the fin 12, as clearly shown in Figure 3. A plug 15, formed of the same material as the base 10 and designed to fit within the hollow post 11, is provided. The plug 15 has a central bore 16 in which may be positioned a hollow surgical needle 17. The hollow surgical needle 17, as it exits from the plug 15, is bent at an acute angle to the bottom thereof, so as to position the point 18 forwardly of the plug and slightly below the bottom surface of the base 10. The needle 18 has its opening facing upwardly, as clearly shown in the figures.

In practice, the space between the tip of the needle and the bottom of the base 10 will be carefully adjusted so as to give the proper depth injection. As pointed out above, it is usually desired that this distance be such that the needle will completely penetrate the epidermis and reach into the capillary section just above the corium. However, in subcutaneous injections, the needle may be disposed at an angle approaching 30° from the plane of the base 10.

The interior of the post 11 above the plug 15 is hollow, and it is contemplated that this space can be filled with any desired injecting material, such as sera, allergy inoculations, or antitoxins.

In operation, the device will be taken between the thumb and first finger of an operator and placed flat, with the bottom of the base section 10 lying directly on the surface of the skin. A short push of the device along the skin in the direction of the needle will cause the tip of the needle to penetrate the epidermis, as shown in Figure 3. With the needle thus in place the operator will collapse the thin walls of the post 11 in the space above the plug 15 and thus inject the desired injection between the skin of the patient. The bottom of the base 10, as it contacts the surface of the skin, acts as a planing guide and assures that the needle will penetrate to just exactly the desired depth, and the V-shaped opening formed by the cutout portions 13, 14 serves to slightly pinch the skin and somewhat raise it to insure puncture by the needle.

While there has been described what is at present considered a preferred embodiment of the present invention, it will be appreciated by those skilled in the art that various changes and modifications can be made therein without departing from the essence of the invention, and

it is intended to cover herein all such changes and modifications as come within the true spirit and scope of the appended claims.

I claim:

1. An injector comprising: a base member having an extended skin contacting surface; a member associated with said base member and having a hollow portion adapted to be filled with fluid; and a hollow needle communicating with said hollow portion and having a part extending below and substantially parallel to said skin contacting surface.

2. An injector as set forth in claim 1 in which said needle has a pointed end and an upwardly disposed opening adjacent said end.

3. An injector as set forth in claim 2 in which said end is disposed forwardly of said skin contacting surface and below said surface a distance substantially equal to the thickness of a normal human epidermis.

4. An injector comprising: a base member having an extended skin contacting surface; a member associated with said base member and having a hollow portion adapted to be filled with fluid; a plug closing said hollow portion; a hollow needle in said plug communicating with said hollow portion and having a part thereof extending below and substantially parallel to said skin contacting surface.

5. An injector comprising: a base member having an extended skin contacting surface; a member associated with said base member and having a hollow portion adapted to be filled with fluid; a plug closing said hollow portion; a hollow needle in said plug communicating with said hollow portion and having a part thereof extending below and substantially parallel to said skin contacting surface in which said hollow portion has thin walls adapted to be compressed by the fingers to eject said fluid, and in which said end is disposed forwardly of said skin contacting surface and below said surface a distance substantially equal to the thickness of a normal human epidermis.

6. An injector comprising: a base member having a substantially flat and extended skin contacting surface; a hollow post upstanding from said base member and having a closed upper end; a plug in the lower end of said post; and a hollow needle in said plug communicating with said hollow post and having a part extending below and substantially parallel to said skin contacting surface.

7. An injector comprising: a base member having a substantially flat and extended skin contacting surface; a hollow post upstanding from said base member and having a closed upper end; a plug in the lower end of said post; and a hollow needle in said plug communicating with said hollow post and having a part extending below and substantially parallel to said skin contacting surface, in which said needle has a pointed end and an upwardly disposed opening adjacent said end.

8. An injector comprising: a base member having a substantially flat and extended skin contacting surface; a hollow post upstanding from said base member and having a closed upper end; a plug in the lower end of said post; and a hollow needle in said plug communicating with said hollow post and having a part extending below and substantially parallel to said skin contacting surface, in which said hollow post has thin walls

adapted to be compressed by the fingers to eject said fluid, in which said needle has a pointed end and an upwardly disposed opening adjacent said end, and in which said end is disposed forwardly of said skin contacting surface and below said surface a distance substantially equal to the thickness of a normal human epidermis.

9. An injector as set forth in claim 6 in which said base is provided with a substantially vertically extending fin adapted to be gripped by the fingers of an operator for pushing the injector forwardly over the skin of a patient.

10. An injector as set forth in claim 6 in which said base is provided with a substantially V-shaped notch adjacent said needle part adapted to pinch the skin of a patient upon forward sliding motion of said injector thereon.

11. An injector comprising: a base member having a substantially flat and extended skin contacting surface; a hollow post upstanding from said base member and having a closed upper end; a plug in the lower end of said post; and a hollow needle in said plug communicating with said hollow post and having a part extending below and substantially parallel to said skin contacting surface, said hollow post having thin walls adapted to be compressed by the fingers to eject fluid contained therein; said needle having a pointed end and an upwardly disposed opening adjacent said end; said end being disposed forwardly of said skin contacting surface and below said surface a distance substantially equal to the thickness of the normal human epidermis; said base being provided with a substantially vertically extending fin adapted to be gripped by the fingers of an operator for pushing the injector forwardly over the skin of a patient.

12. An injector comprising: a base member having a substantially flat and extended skin contacting surface; a hollow post upstanding from said base member and having a closed upper end; a plug in the lower end of said post; and a hollow needle in said plug communicating with said hollow post and having a part extending below and substantially parallel to said skin contacting surface, said hollow post having thin walls adapted to be compressed by the fingers to eject fluid contained therein; said needle having a pointed end and an upwardly disposed opening adjacent said end; said end being disposed forwardly of said skin contacting surface and below said surface a distance substantially equal to the thickness of the normal human epidermis; said base being provided with a substantially V-shaped notch adjacent said needle part adapted to pinch the skin of a patient upon forward sliding motion of said part thereon.

13. An injector comprising: a base member having a substantially flat and extended skin contacting surface; a hollow post upstanding from said base member and having a closed upper end; a plug in the lower end of said post; and a hollow needle in said plug communicating with said hollow post and having a part extending below and substantially parallel to said skin contacting surface, said hollow post having thin walls adapted to be compressed by the fingers to eject fluid contained therein; said needle having a pointed end and an upwardly disposed opening adjacent said end; said end being disposed forwardly of said skin contacting surface and below said surface a distance substantially equal to the thickness of the normal human epidermis; said base being provided with a substantially vertically extending fin adapted to be gripped by the

fingers of an operator for pushing the injector forwardly over the skin of a patient; said base being provided with a substantially V-shaped notch adjacent said needle part adapted to pinch the skin of a patient upon forward sliding motion of said part thereon.

14. A plug assembly for use in connection with an injector including a base having an extended skin contacting surface and an upstanding, thin walled, hollow cylindrical portion formed thereon, comprising: a plug member adapted to fit within said cylindrical portion and fill a substantial part thereof; a hollow needle within said plug and having an end extending through the upper end of said plug and having its lower end bent substantially parallel to the bottom of said plug so as to lie substantially parallel to said extended skin contacting surface when said plug is inserted in said base.
